COMBINED MAGNETIC RECORDER AND REPRODUCER

Sheldon Lee Pastor, Chicago, and Eugene R. Russell,
Barrington, Ill., assignors to Revere Camera Company,
Chicago, Ill., a corporation of Delaware

Application January 14, 1955, Serial No. 33,990

Term of patent 14 years

(Cl. D26—14)

The single figure of the drawing is a perspective view of a combined magnetic recorder and reproducer showing our new design.

The dominant features of our design reside in the portions shown in full lines.

We claim:

The ornamental design for a combined magnetic recorder and reproducer, as shown and described.
